[57] CLAIM

The ornamental design for a vacuum draining unit for lubricants from internal combustion engines, substantially as shown.

DESCRIPTION

FIG. 1 is a front elevational view of a vacuum draining unit for lubricants from internal combustion engines showing my new design;

FIG. 2 is a right side elevational view thereof;

FIG. 3 is a left side elevational view thereof;

FIG. 4 is a rear elevational view thereof; and

FIG. 5 is a top plan view thereof.

Fig. 1.

Fig. 2.

Fig. 3.

Fig. 4.

Fig. 5.
